UNITED STATES PATENT OFFICE.

HENRY A. BURLINGAME, OF CENTRAL FALLS, RHODE ISLAND, ASSIGNOR TO
THE SAWYER SPINDLE COMPANY, OF BOSTON, MASSACHUSETTS.

SPINNING-SPINDLE AND SUPPORT THEREFOR.

SPECIFICATION forming part of Letters Patent No. 425,930, dated April 15, 1890.

Application filed July 25, 1889. Serial No. 318,662. (No model.)

To all whom it may concern:

Be it known that I, HENRY A. BURLINGAME, of Central Falls, county of Providence, State of Rhode Island, have invented an Improvement in Spinning-Spindles and Supports. Therefor, of which the following description, in connection with the accompanying drawings, is a specification, like letters and figures on the drawings representing like parts.

10 This invention has for its object the production of a novel light-running spindle adapted to yield to variations in load, and thus avoid injurious jar or gyration.

Prior to my invention spindle-bolsters have been provided with ball-like enlargements seated to rock or tip within a surrounding case or sleeve; but in this my invention a part of the spindle is seated on and rotates outside of a ball carried by a spindle-support, a steadyng-pin in line with the center of the spindle being extended through the said ball or into a bolster therein, as will be described.

My invention consists, essentially, in the combination, with a spindle and its whirl made in two parts and each provided with a spherical surface falling inside the whirl when united together, of a support for the spindle having a spherical surface engaged 30 by the spherical surface of the spindle and whirl and supporting the spindle; also, in the combination, with a non-rotating spindle-support having an external ball-like engagement at its upper end, of a spindle having a spherical surface distributed about and supported by the said support at a point outside the center of rotation of the spindle and resting in contact with said enlargement, and also in the combination, with a spindle-support having a spherical seat at or near its upper end and having a longitudinal opening, of a sleeve-whirl spindle having a spherical surface to rest on the said support and a steadyng projection to enter the said support.

Other features of my invention will be hereinafter described, and pointed out in the claims at the end of this specification.

Figure 1 in partial elevation and section 50 shows a spindle and bearing embodying my

present invention; Fig. 2, a section in the line $x-x$ of Fig. 1. Fig. 3 shows opposite side elevations of the bolster or tube extended into the spindle-support, and Figs. 4 and 5 show details to be described.

The rail A has secured to it by nut B a curb C, having a threaded shank C', the curb being shown as provided with a cover C² to aid in preventing lint and dust entering the curb and the oil which may be therein. The shank of the curb is shown as screw-threaded internally (see Fig. 1) to receive the shank of the spindle-support a, (also shown as threaded, the said threads in engagement one with the other,) besides keeping the support and the part C' together, also affording means for the vertical adjustment of the support, and by making the threads rather coarse a loose fit may be made between the said threads, so as to permit a limited amount of lateral movement or looseness to enable the support to move laterally. The support at or near its upper end is provided with a spherical seat a'. (Represented in Fig. 1 as a ball-like enlargement.) The support may and preferably will have within the central opening therein a bolster or sleeve, as b, (shown separately in Fig. 3,) and to prevent the rotation of the said bolster with the spindle its lower end may be slotted, as at b', to embrace or engage a pin or projection b². (See Fig. 1.)

The spindle is composed of two sections—viz., the body c and the sleeve-whirl c'—screwed together at 29, thereby enabling the spindle to be screwed into the whirl to effect longitudinal adjustment of one with relation to the other to compensate for wear between the spindle and whirl on the one hand and the support a on the other. The body has a spherical surface, as at 2, (shown in Fig. 1 as a concavity,) and the whirl c' has a spherical surface at 3, it also being shown in Fig. 1 as a concavity, the spherical surfaces of the body and whirl, as the body and whirl are secured together, fitting spherical surfaces of the spindle-support and rotating thereon. The spherical surface of the support comes in the line of the band-pull and is located within the whirl and is equally distributed about the center of rotation of the spindle.

The spindle-body will preferably have a steadyng pin or projection, as *d*, to extend down into the bolster loosely; but the said pin does not need to rest at its lower end on a step, for the weight of the spindle is carried by the support having the spherical surface. The support *a* is surrounded below the whirl with two sleeves or shields *e f*, one over the other, each of the said shields having oil-holes 5 6 7 and 8 9 10, the partial rotation of the shield *f* on the shield *e* uncovering the said oil-holes, so as to permit oil to come into the bolster through the hole 12 by way of the holes 9 and 6, and also additionally into the upper part of the hole 12 by the holes 8 and 5, the oil in the rotation of the spindle following up the said projection *d* over the top of the bolster and of the support *a*. Should it be desired to cut off admission of oil through the openings 5, 8, 9, and 6, a half-rotation of the sleeves *e* and *f* would bring the holes 10 and 7 opposite the upper part of the hole 12 and a less amount of oil would be admitted. The shield *e* shown as split at 14 from end to end (see Fig. 4) is slipped over the spindle-support *a*, between its threaded shank and the under side of the ball *a'*, as shown in Figs. 1 and 2, and the sleeve *f* is fitted outside the sleeve *e* and inside the hub *h* of the whirl, the sleeve *f* receiving part of the wear of the whirl. The openings 5 and 7 are diametrically opposite each other, as are also the openings 8 and 10. These openings are to aid in regulating or controlling the admission of oil from the box or space inside the curb to the bolster or sleeve and pin *d* or to cut off the flow of oil, that depending upon the position of the sleeves and their openings with relation to each other.

40 I claim—

1. A spindle and its whirl made in two parts and each provided with a spherical surface falling inside the whirl when united together, combined with a support for the spindle, the said support having a spherical surface engaged by the spherical surface of the spindle and whirl and supporting the spindle, substantially as described.

2. A sleeve-whirl spindle, combined with a non-rotating spindle-support having a spherical extension, around which the spindle and whirl are fitted externally, and on which the spindle and whirl rotate, said spindle and

whirl being longitudinally adjustable with relation to each other to thereby compensate for wear, substantially as described.

3. A non-rotating spindle-support *a*, having an external ball-like enlargement at its upper end, combined with a spindle having a spherical surface distributed about and supported by the said support *a* at a point outside the center of rotation of the spindle and resting in contact with said enlargement, substantially as described.

4. A spindle-support having a spherical seat at or near its upper end and having a longitudinal opening, combined with a sleeve-whirl spindle having a spherical surface to rest on the said support, and with a steadyng projection *d* to enter the said support, substantially as described.

5. A spindle-support having a spherical seat at or near its upper end and having a longitudinal opening and a bolster therein, combined with a sleeve-whirl spindle having a spherical surface to rest on the said support, and with a steadyng projection *d* to enter the said support and bolster, substantially as described.

6. A spindle-support having a ball-like upper end, combined with a spindle having a concaved seat to rest on and surround the said ball-like end to be supported thereby, substantially as described.

7. A spindle-support having a spherical or ball-like upper end and screw-threaded at its lower end and a threaded shank *C'*, into which it is inserted, combined with a sleeve-whirl spindle having a concavity to fit the said spherical or ball-like enlargement, the latter supporting the spindle in its rotation, substantially as described.

8. The sleeve-whirl spindle having spherical surfaces 2 3 and a steadyng-pin *d*, and the support having a spherical or ball-like end to sustain the spindle in its rotation, and a bolster, combined with a pin or projection to restrain the rotation of the bolster with the spindle, substantially as described.

In testimony whereof I have signed my name to this specification in the presence of two subscribing witnesses.

HENRY A. BURLINGAME.
